UNITED STATES PATENT OFFICE.

ARRA LEONE ADAMS, OF ARKADELPHIA, ARKANSAS.

DESIGN FOR A BAG.

47,064.

Specification for Design.

Patented Mar. 9, 1915.

Application filed October 15, 1914. Serial No. 866,869. Term of patent 14 years.

To all whom it may concern:

Be it known that I, ARRA LEONE ADAMS, a citizen of the United States, residing at Arkadelphia, in the county of Clark and State of Arkansas, have invented a new, original, and ornamental Design for Bags, of which the following is a specification, reference being had to the accompanying drawing, forming a part thereof, in which—a rear elevation of a bag showing my new design.

I claim:

The ornamental design for a bag, as shown.

ARRA LEONE ADAMS.

Witnesses:

S. M. BETTS,
J. B. NICHOLS.
